(57) **CLAIM**

The ornamental design for a part of a charging station for electric vehicles, as shown and described.

DESCRIPTION

The file of this patent contains at least one drawing executed in color. Copies of this patent with color drawings will be provided by the Office upon request and payment of the necessary fee.

Fig. 3.1 is a top plan view of my new design for a part of a charging station for electric vehicles;

Fig. 3.2 is a perspective view thereof;

Fig. 3.3 is a front elevation view thereof; and

Fig. 3.4 is a rear elevation view thereof.

The broken lines depict portions of the part of a charging station for electric vehicles that form no part of the claimed design.
